United States Patent [19]

Fujino

[11] Patent Number: Des. 362,197

[45] Date of Patent: ** Sep. 12, 1995

[54] APPARATUS FOR MEASURING ELECTRIC FIELD STRENGTH

[75] Inventor: Yoshio Fujino, Kobe, Japan

[73] Assignee: DX Antenna Co., Ltd., Hyogo, Japan

[**] Term: 14 Years

[21] Appl. No.: 29,251

[22] Filed: Sep. 30, 1994

[30] Foreign Application Priority Data

Mar. 30, 1994 [JP] Japan 6-8990

[57] CLAIM

The ornamental design for an apparatus for measuring electric field strength, as shown.

DESCRIPTION

FIG. 1 is a top and front perspective view of a first embodiment of the apparatus for measuring electric field strength;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a bottom view thereof.

FIG. 1

FIG. 2

FIG. 3

FIG. 4

FIG. 5

FIG. 6

FIG. 7
